RADIATOR

Dwight Tenney, Newark, N. J.

Application January 10, 1934, Serial No. 706,129

15 Claims. (Cl. 257—144)

This invention relates to radiators and in particular to radiators of the encased type for heating a stream of air forced through the radiator by a fan or blower.

5 An object of the invention is to devise an improved radiator construction which will transfer a maximum amount of heat to the air and offer a minimum resistance to the flow of the air.

10 A further object is to devise a generally improved radiator construction in which the amount of material required and the space occupied by the radiator for a given air capacity is greatly reduced over prior arrangements.

15 Another object is to devise a radiator construction in which all available radiating surface is utilized for heating the air.

20 Another specific object is to provide a steam radiator construction to facilitate the drainage of the condensate from the radiator and to prevent the formation of air pockets.

The invention is illustrated in the accompanying drawings in which:

25 Figure 1 is a side elevational view of the preferred form of my radiator with one side plate removed;

Figure 2 is a sectional view along line 2—2 of Figure 1;

30 Figure 3 is a sectional view of Fig. 1 along line 3—3, with certain parts omitted;

Figure 4 is a side view of a second form of radiator according to my invention;

35 Figure 5 is a sectional view along line 5—5 of Figure 4, with certain parts omitted;

Figure 6 is a side view of a third form of radiator;

Figure 7 is a sectional view of Figure 6 along line 7—7, with certain parts omitted;

40 Figure 8 is a side view of a fourth form of radiator;

Figure 9 is a side view of a semi-circular form of radiator;

Figure 10 is a sectional view of Figure 9 along line 10—10, with certain parts omitted;

45 Figure 11 is a detail view illustrating the air flow around two different forms of heater tube;

Figure 12 is a series of curves illustrating the operating characteristics of my improved radiator.

50 Referring to Figures 1 to 3, the preferred form of my radiator construction comprises an enclosing sheet metal casing formed of two side plates 1a and 1b, a top plate 1c, and a bottom plate 1d. The plates forming the casing are held in position by a suitable frame formed of angle-bars

as illustrated in the drawings. Side plate 1b has been omitted in Figure 1 to show the internal construction of the radiator. Mounted within the casing are two V-shaped headers 2 and 3, one above the other, and a number of U-shaped heater tubes 4 are connected between the headers as shown. Arranged within the casing are a pair of vertical plates 1e and 1f and a horizontal plate 1g positioned to define upper and lower main air channels or passages A and B through the radiator, and also to define two side passages or ducts C and D in which are located the bends or loops of the U-tubes and the headers, respectively. It will be noted that the upper legs of U-tubes 4 are located in passage A and are connected with header 2, while the lower legs of the tube pass through passage B and are connected with the V-header 3. Figure 3 shows the arrangement of the tubes with respect to the passages A, B, C and D; only two U-tubes being shown, the remainder being omitted for the sake of clearness of illustration. Any suitable method of connection of the U-tubes to the headers may be employed, such as by welding, or by the threaded connections 4a indicated in Figure 3. For the sake of clearness of illustration, the threaded connections have not been shown in Fig. 2. Header 2 is provided with an inlet extension 2a at the bottom of the V and extending to the outside of the casing through plate 1b, and header 3 is provided with an outlet extension 3a at the bottom of the V and passing through the bottom plate 1d. Each of the U-tubes 4 is provided with spaced radiating fins 4b formed of thin sheet metal of good heat conductivity. These radiating fins are provided on the tubes in the main passages A and B and have been illustrated in Figures 2 and 3 on two of the tubes only. I prefer to use square fins of a size such that the air stream must come into contact with at least two fins in passing through a row of heater tubes, as will be clear from Figure 1. If desired, circular fins may be employed, or the well known helix form of fin construction may be used. A small vertical baffle 1d' extends upwardly from the middle of plate 1d between the lower legs of the two center U-tubes to prevent the air from by-passing these tubes. A like baffle 1g' extends upwardly from plate 1g between the upper legs of the center U-tubes for the same purpose. Similar baffles 1c' and 1c'' extend downwardly from plate 1c on the outside of the upper legs of the two end U-tubes, and baffles 1g'' and 1g''' extend downwardly from plate 1g on the outside of the lower legs of the

two end U-tubes, to force the air to pass on the inside of the tubes.

As will be seen from the drawings, the radiator construction in each of the main air passages A and B is the same, and in each case, two rows of heater tubes are arranged at opposite angles across the passage, so that in passing through the radiator the air must pass through both rows of heater tubes. The amount of resistance offered to the flow of air through the radiator and also the amount of heat transferred to the air, will depend upon the size and the spacing of the heater tubes and also the length of the heater passage. The smaller the tube and the wider the spacing, the smaller will be the resistance to flow, but the heat transferred will also be smaller. In the design of my radiator I have attempted to obtain the maximum amount of heat transfer while maintaining low resistance to flow of the air. In radiators of the forced draft type the transfer of heat from the heater tubes to the air is principally by radiation and by conduction through direct contact of the air with the tubes and fins. It is, therefore, important to keep the air in intimate contact with the tubes and fins as long as possible, but too great a density of radiating surface and too long a passage will unduly increase the friction and pressure drop across the radiator and will thereby greatly increase the amount of power required to force the air through the radiator. In my radiator I obtain good heat transfer with low resistance to flow by making my heat passage longer than has been the usual practice and distribute the heater tubes along the passage in a manner to obtain full benefit of both the radiation and conductive transfer of heat without increasing the resistance. I have found that the spacing of the heater tubes depends upon the size of the tube and the size of the air passage through the radiator. I prefer to provide a number of tubes in each row or arm of the header such that the projected area in a plane at right angles to the axis of the passage will be substantially equal to the area of the passage, and the heater tubes are spaced apart a distance such that the combined open area between the tubes is at least equal to the cross-sectional area of the air passage. According to these design considerations, for best results, the angle of each header arm to the horizontal should be of the order of 30 degrees when there is substantially no over-lap of the projected area of the tubes and will be less than 30 degrees where the tubes overlap in projected area.

Due to the fact that the plate 1g does not extend into the passages C and D, and also due to the absence of the radiating fins, these passages offer less resistance to the flow of air than the main heating passages A and B. I utilize passages C and D to by-pass air around the main heating passages A and B, and by properly designing the passages C and D with respect to the main passages A and B it is possible to obtain any desired pressure drop across the radiator. If desired, suitable dampers C1 and D1 (see Fig. 2) may be provided to control the amount of air which is by-passed through the passages C and D, respectively, and thereby control the effective resistance of the radiator. Also, suitable dampers A1 may be provided in front of the main passages A and B, and these dampers may be operated by a common operating element arranged to open dampers C1 and D1 when closing dampers A1, and vice versa. By this arrangement it

is possible to control the final temperature of the air leaving the radiator through a limited range, and by properly proportioning passages C and D with respect to passages A and B a wide variation of the temperature range may be obtained. Air is forced through the radiator by any suitable means such as a fan or blower, indicated in dotted lines at F, which may be driven from any suitable source of power. While the fan is shown only in connection with Figure 1, it will be understood that the other forms of radiators disclosed are also of the forced draft type.

In Figure 12 I have given a series of curves showing the operation of a radiator constructed in accordance with Figures 1 to 3 and also the operation of a radiator of the usual "bank type" in which the air is passed broadside through a bank of heater tubes. The dotted line curves illustrate the operation of a three-row bank type 20 of radiator while the solid line curves illustrate the operation of a radiator constructed according to my invention which produces substantially the same final temperatures of air as the bank type radiator for the same pressure drop, the air being introduced at 55° F. with steam supplied to both radiators at a pressure of 5 pounds per square inch. Curves (1) and (1a) indicate the weight of condensate in pounds per hour per foot of heater tube for varying pressure drop across 30 the radiators. Curves (2) and (2a) indicate the relation between the pressure drop across the radiator in inches of water and the volume of air flowing through the radiator in cubic feet per minute per foot of radiator tubing. Curves (3) and (3a) indicate the final temperature of the air leaving the two radiators when operating at different static pressure drops. By comparing curves 1 and 1a, it will be seen that the weight of condensate per linear foot of heater pipe in 40 my improved radiator greatly exceeds that obtained in the ordinary bank type radiator. Since the weight of condensate is a direct indication of the amount of heat transferred, it will be seen that for a radiator having the same length of 45 heater tubing, my construction is far superior to the bank type of construction. Also, by comparison of curves 2 and 2a, it will be seen that for the same drop in pressure across the radiator, my construction permits more than double the 50 volume of air to be passed through the radiator and delivered at approximately the same final temperature than in the case of the bank type radiator.

In Figures 4 and 5, I have shown a modification of my radiator construction generally like that illustrated in Figures 1 to 3, and corresponding parts are indicated by like reference numerals. In this construction, the radiator is divided into four main air passages A, B, E and F by horizontal plates 1g, 1h and 1i. Headers 2 and 3 are located at the top and bottom respectively, of header passage D, and the heater tubes 4 connected between the header are looped and passed through the main passages A, B, E and F in the manner shown in Figure 5, only one looped tube being shown for the sake of clearness of illustration. It will also be understood that various details of construction, such as the reinforcing frame work, the radiating fins, and other details of construction have been omitted from Figures 4 and 5. The operation of this modification will be apparent from the foregoing description of operation of Figure 1.

A third arrangement of radiator is shown in

Figures 6 and 7 where instead of employing V-type headers, I use two straight headers 5 and 6 between which U-tubes 4 are connected, and the upper and lower walls of the casing, as well as the central plate 1g, are formed so that opposite sections of the main passages A and B lie at opposite angles to the axis of the headers as illustrated in Figure 6. By this construction, the air in each passage is passed through one row of heater tubes twice, once on the up-slope of the passage and once on the down slope. The amount of the angle between the headers and the passage and the size and spacing of the heater tubes in this case are determined by the same considerations as described above for Figure 1. Constructional details described above for Figures 1 to 3 may be used in this construction but have not been shown in the drawings.

In Figure 8 I have illustrated another arrangement of radiator in which the main air passages are straight, and straight headers 7 and 8 are arranged within the header passage at an angle to the main passages with the tubes 4 connected between and passing through main passages A and B as shown. This construction results in an arrangement substantially equivalent to one end section of the arrangement illustrated in Figure 1, and its operation will be readily understood. If desired, the casing of Figure 8 may be extended and another loop-tube and header assembly like that shown may be inserted and arranged at the same or opposite angle with respect to the passages. Headers 7 and 8 are provided with inlet and outlet connections 1a and 8a located at the lowermost ends of the headers to facilitate drainage of the condensate from the radiator.

In Figures 9 and 10 I have illustrated a radiator arrangement in which the headers 9 and 10 are formed as semi-circular tubes arranged within a casing of generally semi-circular construction, the center of the headers being eccentric to the center of the casing in such manner that the rows of heater tubes 4 cross the two main passages A and B twice in the length of the passages as shown in Figure 9. An inlet 9a is provided at the lowermost point of header 9 and an outlet 10a at the lowest point in header 10. Only one U-tube has been shown in Figure 10, and other details of construction have been omitted to avoid confusion of illustration.

In Figures 1, 4, 8 and 9, it will be seen that the constructions involve headers which are inclined at an angle to the horizontal, and inlet and outlet connections are made to these headers at the lowermost point, the inlet being in the upper header and the outlet in the lower header. This construction makes it possible for both the steam and the condensate to flow in the same direction, and facilitates the drainage of the condensate from the radiator coils. Also, in Figures 1, 4 and 9, since the inlet and outlet passages are located in the middle of the header tubes, the steam velocity within the headers is materially reduced over that in the supply pipe.

In order to reduce the resistance to flow of air through the radiator and to obtain a more intimate contact of the air with the heater tubes I may use heater tubes having a streamline section instead of circular section. In Figure 11 I have shown the direction of air currents flowing through a line of heater tubes with attached fins, the tube at the left having a circular section while the two remaining tubes are formed with streamline sections. It will be noted that in the case of the circular tube, eddy currents are set up behind

the tube and a partial vacuum is created at this point, thus increasing the resistance and preventing good contact of the air with the pipe. In the case of the streamline section, the air flows smoothly over the tube surface, the friction is reduced, and a greater radiating surface is presented to the air. Streamline tubing may be used in all forms of radiator construction described above.

While my radiator is primarily designed as a forced draft radiator, it will be clear that it may also be used as a gravity draft radiator where the circulation of air is caused by convection. It will also be understood that instead of using the radiator to transfer heat from the tubes to the air flowing through the radiator, the radiator may be used to cool the air by supplying the tubes with a cooling fluid. Accordingly, the term "radiator" as used in the following claims is to be broadly interpreted to cover either function.

Various modifications of my invention will be obvious to those skilled in the art, and all such modifications as fall within the terms of the appended claims are considered as falling within the scope of my invention.

What I claim is:

1. In a radiator, the combination of a pair of V-shaped headers arranged one above the other, a plurality of U-tubes connected between said headers, and a casing for enclosing the opposite legs of said U-tubes in separate air passages.

2. In a radiator, the combination of a V-shaped header having an inlet formed at the bottom thereof, a second V-shaped header arranged below the first header and having an outlet formed at the bottom thereof, a plurality of U-tubes connected between said headers, a casing for enclosing said U-tubes, and a partition in said casing forming two air passages including the opposite legs of said U-tubes.

3. In a radiator, the combination of a casing provided with two main air passages one above the other and auxiliary air passages on opposite sides of the casing, a pair of V-shaped headers located in one of said auxiliary passages opposite said main passages, a plurality of U-tubes connected between said headers and having opposite legs thereof extending through said two main passages and the loops thereof located in the second auxiliary passage.

4. In a radiator, the combination of a pair of headers, a plurality of U-tubes connected between said headers, and a casing for enclosing the opposite legs of said U-tubes in separate air passages arranged in parallel relation.

5. In a radiator, the combination of a casing provided with two air passages, a header associated with each passage and arranged at an angle thereto, and a plurality of U-tubes connected between said headers with opposite legs lying in different air passages.

6. In a forced draft radiator, the combination of a casing provided with an air passage, and a row of heater tubes arranged across said passage at an angle to the longitudinal axis of said passage of the order of 30 degrees, said tubes being spaced apart in said row so that the projected area of said tubes at right angles to the axis of said passage is substantially equal to the cross-sectional area of said passage, and the effective area of the space between the tubes is substantially equal to the cross-sectional area of said passage.

7. In a forced draft radiator, the combination of a casing provided with an air passage, and

5 a plurality of rows of heater tubes arranged across said passage, each row being associated with individual linear sections of said passage and arranged at an angle to the longitudinal axis of said passage of the order of 30 degrees, the tubes in each row being spaced apart so that the projected area of said tubes at right angles to the axis of said passage is substantially equal to the cross-sectional area of the passage, and the effective area of space between the tubes in each row is substantially equal to the cross sectional area of said passage.

10 8. In a radiator, the combination of a pair of headers, a plurality of U-tubes connected between said headers, a casing for said headers and tubes provided with a main heating passage, and a by-pass duct enclosing the loops of said tubes.

15 9. In a radiator, the combination of a casing having a main air passage and a by-pass duct, a plurality of U-tubes having their loops located in said duct and their legs extending through the main passage, and a damper for controlling the amount of air by-passed around said main passage through said duct.

20 10. In a radiator, the combination of a casing having a main air passage and a pair of by-pass ducts, a pair of headers located in one of said by-pass ducts, a plurality of U-tubes connected between said headers and having their legs extending thru said main passage and their loops located in the second by-pass duct.

25 11. In a radiator, the combination of a casing having a main air passage and a pair of by-pass ducts, a pair of headers located in one of said by-pass ducts, a plurality of U-tubes connected between said headers and having their legs extending thru said main passage and their loops located in the second by-pass duct, and dampers for controlling the amount of air by-passed through said ducts.

30 12. In a radiator, a casing provided with two side passages and upper and lower main air passages between said side passages, a V-shaped header located in one of said side passages opposite the upper main air passage, a second V-

35 shaped header located in said side passage opposite the lower main passage, a plurality of U-tubes connected between said headers with the upper legs thereof extending through the upper main passage and the lower legs extending through the lower main passage, the loops of said tubes being arranged in the opposite side passage, the arms of said V-headers being arranged at equal angles to the axis of said main passages, and the U-tubes being so spaced within each main passage that the projected area of said tubes at right angles to the axis of said passage is substantially equal to the cross-sectional area of the passage, and the effective area of the space between the tubes is at least equal to the cross-sectional area of the passage, deflecting baffles associated with the uppermost and lowermost tube in each main passage for causing the air to pass to the inside of said tubes, spaced radiating fins attached to said tubes within said main air passages, and dampers provided for each of said side passages, said side passages serving to by-pass air around said main passage.

40 13. In a radiator, the combination of a casing forming an air passage, a pair of spaced headers arranged along one side of said passage at an acute angle to the longitudinal axis of said passage, and a plurality of U-tubes connected between said headers and extending across said passage.

45 14. In a radiator, the combination of a casing forming an air passage, a pair of spaced headers arranged along one side of said passage at an angle to the longitudinal axis of said passage of the order of 30 degrees, and a plurality of U-tubes connected between said headers and extending across said passage.

50 15. In a forced draft radiator, the combination of a casing provided with an air passage, and a row of heater tubes arranged across said passage at an acute angle to the axis of said passage, said tubes having a stream-line cross-section and being positioned to guide the stream of air through said row of tubes with minimum resistance to flow.

45 DWIGHT TENNEY.
